UNITED STATES PATENT OFFICE.

ELLIS E. BROWN, OF READING, PENNSYLVANIA.

FOLDING NET-FRAME.

1,340,874.

Specification of Letters Patent. Patented May 25, 1920.

Application filed October 27, 1919. Serial No. 333,545.

To all whom it may concern:

Be it known that I, ELLIS E. BROWN, a citizen of the United States, residing at Reading, in the county of Berks and State 5 of Pennsylvania, have invented certain new and useful Improvements in Folding Net-Frames, of which the following is a specification.

My invention relates more particularly to 10 collapsible net devices such as are adapted for landing fish, and like purposes; and it consists in an improved collapsible frame formed of resilient strip material, arranged in engagement with a relatively movable 15 handle portion so that the projected portion of the frame will automatically assume a tensioned loop shape, as fully described in connection with the accompanying drawing illustrating a preferred embodiment of the 20 invention. The novel features are clearly pointed out in the claims.

Figure 1. is a longitudinal view showing the handle portion in section, with the frame in open position, and also indicating 25 in dotted lines a position assumed by the resilient frame during the folding or unfolding operation.

Fig. 2. is a corresponding edge view.

Fig. 3. is sectional view of the handle portion as in Fig. 1 but showing the completely collapsed frame within the inclosing handle.

Fig. 4. is an end view of the flared handle portion of the device.

35 The symmetrically curved hoop or horseshoe form of the projected frame indicated in Fig. 1, is adapted to carry a suitably secured net collapsible with the frame, and the tubular handle shown is adapted to neatly inclose both the collapsed frame and net as is most desirable in a conveniently portable device. The main feature of the invention consists in the simple and advantageous construction of the collapsible 40 frame, and the direct engagement of the resilient structure with the relatively movable handle portion to control its collapsing and 45 expanding operation.

The frame as here shown comprises a series of four end-wise connected resilient strips of metal or equivalent material, forming 50 an endless belt of fixed length; the normally parallel main members 5, 5 indicated having a rigid end connection 6, which 55 comprises a disk portion 8 adapted to loosely fit within the tubular frame inclosure 7

forming the handle portion of the complete device; and the projecting free ends of these main members 5, 5 being attached to the respective pivot pins 10, 10 of hinge 60 members 11, 11 rigidly secured to the connecting ends of resilient frame extension members 12, 12 which are themselves hingedly connected at their meeting ends as indicated at 13; such hinged construction 65 permitting of the free folding of the resilient frame structure into the collapsed form indicated in Fig. 3.

The midway hinge connection 13 of the resilient frame extension members 12, 12 is 70 arranged to permit of only a one-way hinge movement, by means, as here shown, of a portion 14 of one of said members projecting beyond the pivotal point so as to limit outward movement while permitting free 75 hinge movement inward to approximately parallel position.

The hinge connection 11, 11 between the main frame members 5, 5 and the extension members 12, 12 permits the latter to be 80 jointly folded inward as indicated in Fig. 3, where the collapsed frame, together with the attached net, is substantially inclosed by the relatively movable tubular handle portion 7.

As the relative position of the collapsed frame and said handle portion 7 is changed, and the extension members 12, 12 are forced outward beyond the withdrawn main members 5, 5, the resilience of the several members causes them to first assume the bent 90 positions indicated in dotted lines in Fig. 1, and then the rigid hoop form shown in full lines; the one-way hinge connection 13 of the extension members compelling the latter 95 to bend while exerting a spreading pressure on the connected main members. To provide for giving improved rigidity and form to the projected frame I preferably extend members 12, 12 beyond their hinge connections 100 11, 11 as overlaps 15, which are adapted to be engaged or disengaged by locking devices 16 slidable on the main members.

The forward portion of the tubular handle 7 is flared in the spreading-plane of the 105 main members 5, 5, as best indicated in Fig. 4, to form guide ways for the bending frame members 5, 5; and is at the same time narrowed at right angles to said spreading plane so as to serve the purpose of limiting the outward movement of the engaged portion of the frame; the edge portion how-

ever being flanged outwardly to provide a distended or bell-mouth opening into which the collapsed net may be readily inserted. The form of the handle device may however be varied from that which is specifically set forth, its essential function being to control the operation of the collapsing frame, and the preferred construction may be otherwise modified within the scope of 10 the invention, as defined in the claims.

What I claim is:

1. In combination with a tubular handle member; a tensioned-loop collapsible net frame, made up of flexible strips forming 15 a pair of main members having fixedly connected end portions slidably guided in said handle member, and a pair of inwardly folding outer members hingedly connected together and to the free ends of the respective 20 main members; said outer members being provided with means for limiting their outward hinge-movements substantially as set forth.
2. In combination with a tubular handle member; a tensioned-loop collapsible net frame made up of flexible strips forming a pair of main members having fixedly connected end portions slidably guided in said handle member, and a pair of inwardly folding outer members hingedly connected to- 30

gether and to the free ends of the respective main members; said outer members having overlapping ends adapted to limit their outward hinge-movements and control the flexure of the strips. 35

3. In combination with a tubular handle member; a tensioned-loop collapsible net frame made up of strips forming a pair of main members having fixedly connected end portions slidably guided in said handle member, and a pair of inwardly folding outer members hingedly connected together and to the free ends of the respective main members; said outer members having overlapping ends adapted to limit their outward 40 hinge-movements and control the flexure of the strips, and said main members having means for clamping said overlapping ends. 45

4. A tensioned-loop collapsible net frame comprising a pair of flexible strip members having fixedly connected end portions provided with a handle-fitting disk, in combination with a tubular handle slidable upon said members and having a mouth portion shaped to form oppositely arranged diverging 50 guide-ways for the strip members and a stop for said handle-fitting disk. 55

In testimony whereof I affix my signature.

ELLIS E. BROWN.
